UNITED STATES PATENT OFFICE.

HENRY L. DEMMLER, OF KEWANEE, ILLINOIS.

MEANS FOR VENTING CORE BOXES.

Application filed August 13, 1921. Serial No. 492,033.

To all whom it may concern:

Be it known that I, HENRY L. DEMMLER, a citizen of the United States of America, residing at Kewanee, in the county of Henry and State of Illinois, have invented a new and useful Means for Venting Core Boxes, of which the following is a specification.

My invention relates to molds or core boxes to be used in connection with mold or core making machines of the so-called Hewlett type, in which a mold or core box is clamped against a sand container from which sand is forced into the mold or core box by compressed air. I find that the compressed air passing into the mold or core box and also the atmospheric air in the empty mold or core box together retard the proper flow of sand into the mold or core box and prevent the proper formation and packing of the sand. The principal object of my invention is to provide for the proper escape of air from the mold or core box by inexpensive and convenient means.

25 In the drawings,—

Figure 1 is a vertical sectional view, somewhat diagrammatic, of a core box embodying the invention in position in a core making machine.

30 Figure 2 is a plan view of a perforated plug forming part of the invention.

Figure 3 is a vertical section of the plug.

Figure 4 is a side elevation of a core box forming part of the invention.

35 Figure 5 is a plan view of the core box.

Figure 6 is a plan view of a plug similar to Figure 2.

The machine illustrated in Figure 1 comprises a frame 1 which supports a pressure head 2 and a sand container 3. The sand container 3 is provided with a removable head 4 and a removable bottom plate 5 formed with an aperture 6, the heads being secured to the sand container by screws *a*.

40 The sand container 3 is connected with a source of compressed air or other pressure fluid by a pipe 13. A piston 9 is vertically slideable on the pressure head 2 and is operable by the control of compressed air or other pressure fluid through the pipe 10 which communicates with a suitable source of supply.

The mold or core is to be formed in the mold or core box 7 by clamping the latter pneumatically between the head of the cylinder 9 and a bottom plate 5 of the sand container and then forcing sand 11 from the sand container 3 into the mold or core box by compressed air. The walls of the mold or core box 7 are formed with apertures in each of which is secured a plug 8 formed with a plurality of small perforations, the perforated surface of the plug forming part of the molding surface of the core box as illustrated in the drawings. It will be understood, of course, that the mold or core box 7 shown in the drawings is illustrative only and may be of any desired form and that the size and location of the apertures in its wall and the size and number of the perforations in the plugs will vary in accordance with the size and form of the mold or core box and with the grade of sand being used. The perforations in the plug, of course, are of such size as to permit the passage of air while preventing the passage of sand, and in practice I find it preferable to make the plugs in the form of perforated brass cups.

45 After a mold or core box has been clamped against the bottom plate of the sand container, compressed air or other pressure fluid is admitted to the sand container and forces the sand into the mold or core box. Egress of sand from the mold or core box is effectively prevented but air may freely escape from the mold or core box in every desirable place and direction, so that the sand will be very compactly and firmly formed in the mold or core box.

Having thus described my invention, what I claim as new and desire to secure by Letters Patent of the United States is:—

1. A mold or core box provided with outlet openings, and perforated plugs secured in the respective openings.

2. A mold or core box provided with outlet openings, and hollow metal perforated cups secured in the respective openings.

3. A mold or core box provided with outlet openings in its molding surface, and perforated plugs secured in the respective openings and forming part of the molding surface.

4. A mold or core box provided with outlet openings in its molding surface, and hollow metal perforated cups secured in the respective openings and forming part of the molding surface.
5. A perforated plug adapted to be secured in a mold or core box, for the purpose described.
6. A hollow metal perforated cup adapted to be secured in a mold or core box, for the purpose described.
- In testimony whereof, I hereunto set my hand.

HENRY L. DEMMLER.
